UNITED STATES PATENT OFFICE.

CARL J. LANDIN, OF BOSTON, MASSACHUSETTS.

ELECTRIC ORGAN-ACTION.

No. 824,079.

Specification of Letters Patent.

Patented June 19, 1906.

Application filed June 3, 1904. Renewed March 16, 1906. Serial No. 306,384.

To all whom it may concern:

Be it known that I, CARL J. LANDIN, a citizen of the United States, residing at Boston, in the county of Suffolk and State of Massachusetts, have invented new and useful Improvements in Electric Organ - Actions, of which the following is a specification.

This invention relates to an electric organ-action; and the object of the invention is to provide a simple, economical and quick-acting article of this character.

In pipe-organs, where it is essential that an effective electrically-controlled valve should be provided, my said improved action is particularly advantageous in view of the rapidity of its operation, the economy of the action being due to the fact that but a small amount of current is necessary to bring about the operation of the same.

The said electric action involves in its organization a solenoid of novel construction, but which is not claimed *per se* herein, one simple adaptation of which is illustrated clearly in the accompanying drawings, forming a part of this specification, and which will be set forth in detail in the following description. In said drawings I also illustrate one use to which the said action may be put; but I wish to state at this point that I do not limit myself to this particular use, for the reason that the action may be employed equally well in other places in an organ, nor do I limit myself to the exact organization of electric action disclosed by said drawings and description, for I may vary the same as to a number of details and like matters within the scope of my claims succeeding said description.

Referring to the drawings, Figure 1 is a sectional elevation of a portion of a pipe-organ with an electric action illustrated in connection therewith and involving an embodiment of my invention. Fig. 2 is a detail in elevation of the core for the solenoid represented in the preceding figure.

Like characters refer to like parts throughout the views.

I will set forth the construction and relation of the parts represented in Fig. 1, the same showing a portion of a pipe-organ. My improved electric action is, as will be gathered from the initial statements of my specification, of particular advantage in connection with the parts represented in said figure; but, as previously intimated, such action may be

used in conjunction with other mechanism of the organ. Referring to said figure, the numeral 5 denotes an air-chamber the air-pressure in which may be derived from any suitable source. The chamber 5 is in the nature of a main chamber, an auxiliary or stop chamber being represented by 6 in said Fig. 1 and as communicating with said main or air chamber by a passage or windway, as 7. In the stop or auxiliary chamber 6 is situated an opening adapted to be closed by a flexible diaphragm 8, connected with one end of a stem or rod 9, said stem being provided near its opposite end with a disk or equivalent valve, as 10, adapted to control the port 11 and the port 12 opening into the channel 13, which channel, it will be perceived, extends from the port 11 to a second port, as 14, closed at its inner end by a flexible diaphragm, as 15, on one end of a stem or rod 16. The rod 16 carries near its opposite end two valves, as 17 and 18, of a suitable nature, controlling the opposite ends of the port 19, opening at its inner end into the stop-chamber 6 and at its outer end to the atmosphere. A channel, as 20, leads from the port 19 to the pipe 21, and it will be apparent that upon the delivery of a blast of air of sufficient intensity through the channel 20 into the pipe 21 the latter will be caused to speak or sound. The opening which is closed by the flexible diaphragm 8 is the inner enlarged end of the channel or windway 22, the outer end of said channel opening into the chamber 23 below the air-chamber 5.

In the bottom of the chamber 23 is threaded a nipple 24, the open under side of which is flush with the lower surface of the casing containing the several chambers. The nipple communicates with the atmosphere, the top thereof being controlled by a valve, as 25, hereinafter more particularly described. Said valve is normally held seated against the upper open end of the nipple or pipe-section 24 by pressure of air thereagainst, as will hereinafter appear, assisted by gravity in order to permit the direction of air from the chamber 5 in a manner hereinafter described into the channel or windway 22, where such air can act against the flexible diaphragm 8 in order to press the same toward the right in Fig. 1, thereby moving the stem in a corresponding direction, whereby the valve 10 will be caused to uncover the outer end of the port 11 and be caused to simultaneously close the port 12, leading to

the atmosphere, so that the air which had passed into the chamber 6 from the chamber 5 by way of the windway 7 can enter the lower end of the channel 13 to traverse the latter and to enter the port 14 to act against the diaphragm 15 and press the same toward the left. When the diaphragm 15 is thus operated, the stem or rod 16 is correspondingly moved, so as to force the valve 17 against the inner end of the port 19 and the valve 18 away from the outer end of said port for preventing pressure in the chamber 6 from entering said port 19 and for putting simultaneously the pipe 21 into communication with the atmosphere.

The duplex valve 25, as previously stated, is normally held seated against the nipple 24, and this relation may be brought about simply by the air-pressure thereagainst augmented by the weight of said valve and that of an armature, hereinafter described, connected therewith, or means, such as a spring, may be provided for aiding the air-blast and gravity in holding the valve against the nipple 24. Upon the energization of the electrically-governed operating member for the duplex valve 25, which member, as will hereinafter appear, is a solenoid of peculiar construction, the valve 25 will be so moved as to 30 uncover the open upper end of the nipple 24 and simultaneously, as will hereinafter appear, to cut off the flow of air from the chamber 5 to the channel or windway 22. The instant that the valve is thus actuated to cut off the supply of air to the channel or windway 22 the air in the latter can flow therefrom into the chamber 23 and from thence into the nipple or equivalent conduit 24 to the atmosphere. When the pressure is reduced in the channel or windway 22 by the operation of the valve 25, the diaphragm 8 is caused to collapse, thereby drawing the valve 10, through the intermediate rod or stem 9, inward and against the outer end of 40 the port 11 and simultaneously away from the port 12 to permit the air in the channel 13 and port 14 to escape to the atmosphere by way of said port 12, whereby the diaphragm 15 will be caused to collapse in order to draw the valve 17, through the medium of the rod 16, away from the inner end of the port 19 and simultaneously draw the valve 18 against the outer end of said port 19, whereby air can flow from the chamber 6 into 50 said port 19, the air passing therefrom by way of the passage 20 to the pipe 21 to sound the same.

The solenoid for operating the valve 25 is denoted in a general way by 30, and it may 60 be either simple or compound wound. Conductors for supplying the solenoid 30 with the necessary electric current supplied by an electric generator are denoted each by 31. The generator may be of any suitable kind, 65 such as a battery or series of batteries, as 32.

The wires 31 lead into what is shown as the upper end of the solenoid 30 for a purpose that will hereinafter appear. While the solenoid is represented as being vertically disposed, this is not essential, as it may be horizontally or otherwise disposed. In like manner I do not limit myself to the disposition of any of the other parts in any particular direction.

The solenoid is preferably, though not necessarily, wound on a metallic tube, as 33, which is ordinarily made from brass in order to decrease the friction between the same and the core 34 of said solenoid. In order to materially increase the attracting power of 70 the solenoid, the winding thereof is represented as surrounded by a soft iron casing, as 34', the rear or bottom head of which is sunk or let into the bottom of the communicating chambers 5 and 6. The core 34 of the solenoid is made, preferably, of soft sheet-iron and is curled into the shape of a tube, so as to constitute, with the tube 33, a conduit for air. Said core has on its rear or lower end a hook or bent projection 35, connected with 80 the valve 25. It will be evident, therefore, that the core for the solenoid is tubular and that the lower end of the same is separated from the valve 25. Said core has a free longitudinal motion in the tube 33. It therefore follows that in view of the tubular core and tube extending through the solenoid air can pass through the two tubular parts from the chamber 5 downwardly to act against the valve 25 to press the same solidly against its seat upon the upper tapered portion of the nipple 24, this being, as previously indicated, the normal relation of the parts.

It will be seen that what might be considered the "lower" end of the tube 33 extends below the corresponding end of the solenoid 30, whereby said end serves as a stop for the valve 25 and its connected core 34, so as to sustain the latter where the magnetic field is strongest in the solenoid when the latter is 100 energized. In addition to this the said tube, acting as a stop in the manner set forth, also acts to hold the upper portion of the core away from the upper part of the iron casing and in this way prevents any residual magnetism that may be in said part of the iron casing when the latter is deenergized from retarding the closure of the valve 25 against its seat upon the upper side of the nipple or pipe-section 24. By virtue also of this relation any residual magnetism that may be in the lower part of the iron casing will have a tendency to pull the core downward when the solenoid-circuit is broken, so as to cause the valve to seat against the nipple 24. 110 When the solenoid-circuit is closed, and this result is secured through the action of an organ-key, as customary in organ-actions, or in any other desirable way, the solenoid will be energized in order to attract its core or to 120 130

pull the same, in the present case upward, in opposition to the pressure of air against the valve 25, whereby said valve will be moved away from the top of the nipple 24 and 5 against the lower end of the tube 33 to thereby cut off communication between the chamber 5 and the windway or channel 22 and permit the reduction of air-pressure in said windway or channel 22. When such operation 10 takes place, the diaphragm 8 is caused to collapse to thereby, through the agency of the intervening parts, quickly move the valve 17 away from the inner end of the port 19 and to permit a blast of air to be supplied to the 15 pipe 21 in the manner hereinbefore described. The moment that the solenoid-circuit is opened the solenoid will be deenergized in order to free the valve 25 from the action of the same, whereby the compressed air in the 20 chamber 5, by passing through the tube 33 and the tube 34, will instantly force the valve 25 against the nipple 24 to resume the normal condition—that is, when the valve seats against the nipple the windway or channel 25 25 is put into communication with the chamber 5 in order to bring about the distension of the flexible diaphragm 8 and through the intermediate parts the movement of the valve 17 against the inner end of the port 19 30 to stop the further supply of air to the pipe. Therefore it will be understood that on the closing of the solenoid-circuit the valve 25 will be instantly caused to uncover the nipple 24 and to cover the tube 33 and that an 35 equally rapid motion will occur on the breaking of such circuit to secure an opposite or return motion of the valve. The rising motion of the valve in opposition to the air-pressure thereagainst is obtained solely by the action 40 of the solenoid, while the return motion of the valve is due to its weight plus that of the core, materially assisted by the air-pressure on said valve, aided by the residual magnetism in the lower part of the solenoid. When 45 the latter is placed horizontally, a spring or other suitable means may be provided to augment the effect of the air-pressure acting against said valve to move the same toward its seat on the nipple 24 or equivalent part. 50 The valve 25 may be of any suitable character. Ordinarily its opposite faces are provided with leather or the like. Said valve 25 is centrally perforated to freely receive the pin 25^a, extending through a perforation in the lateral portion of the hook-shaped projection 35, the pin being represented as a screw having a head at its upper end bearing against the upper side of said lateral portion. The pin or screw 25^a is provided with two 55 nuts 25^b in threaded engagement therewith and between which the valve 25 is loosely mounted.

I claim—

1. In an organ-action, a solenoid, a tube 60 inclosed by the solenoid and projecting be-

yond one end of the same, a tubular core for the solenoid, arranged to move in said tube, a duplex valve operable by said core and adapted to be seated by the core, when the solenoid is energized, against the projecting 70 end of said tube, means for directing a blast of air through the tube and core, and a separate part against which the valve is adapted to be automatically seated when the solenoid is deenergized.

2. In an organ-action, a solenoid, a soft iron casing surrounding the solenoid, a tube inclosed by the solenoid and projecting beyond one end of the same, a tubular core in the solenoid, arranged to move in the tube, a duplex valve operable by said core and adapted to be seated by the core, when the solenoid is energized, against the projecting 80 end of said tube, means for directing a blast of air through the tube and core, and a separate part against which the valve is adapted to be automatically seated when the solenoid is deenergized.

3. In an organ-action, a solenoid, a tube inclosed by the solenoid and projecting beyond one end of the same, a tubular core for the solenoid, arranged to move in the tube and having a projecting portion, a duplex valve connected with the projecting portion of the core at a point beyond the body thereof, said valve being adapted to be seated by the core when the solenoid is energized, against the projecting end of said tube, means for directing a blast of air through the tube and core, and a separate part against 95 which the valve is adapted to be automatically seated when the solenoid is deenergized.

4. In an organ-action, a solenoid having a passage entirely through the same, a tubular core for the solenoid, arranged for movement in the passage, a duplex valve operable by the core and adapted to be seated by the movement of the core, when the solenoid is energized, against one end of the passage, means 105 for directing a blast of air through the passage and core from the opposite end of said passage, and a separate part against which the valve is adapted to be automatically seated when the solenoid is deenergized.

5. In an organ-action, a solenoid, a tube inclosed by the solenoid and projecting beyond one end of the same, a tubular core for the solenoid, arranged to move in the tube, a duplex valve operable by the core and adapted to be seated by said core, when the solenoid is energized, against the projecting end of said tube, an air-chamber in which the solenoid is mounted, the air from the chamber being adapted to enter that end of said tube opposite that against which the said valve seats, a chamber adapted to communicate with the tube, a nipple in the chamber, adapted to communicate with the atmosphere, and against which the valve is adapted to be au- 120 125 130 135

tomatically seated when the solenoid is de-energized, and a windway opening into said chamber.

6. In an organ-action, an air-chamber, a second air-chamber in direct communication with the first air-chamber, an organ-pipe adapted to communicate with the second air-chamber and with the atmosphere, a windway opening into the second chamber and into the atmosphere, a valve for controlling the flow of air through said windway, a diaphragm arranged for operation by an air-blast through said windway, valve mechanism controlled by the diaphragm and adapted to put the organ-pipe into communication with either the second chamber or with the atmosphere, a second windway adapted to communicate with the first chamber or with the atmosphere, a diaphragm adapted to be operated by a blast of air through the last-mentioned windway and adapted to control the first-mentioned valve, a solenoid in the first chamber, having a tube extending through and beyond the same, a tubular core for the solenoid, a duplex valve arranged to be moved against the projecting end of the tube by the core on the energization of the solenoid to thereby put the second windway into communication with the atmosphere, and to be moved away from said tube on the de-energization of the solenoid, to put said second windway into communication with

the first chamber, and a part in communication with the second windway and atmosphere and against which the valve is automatically seated when the solenoid is de-energized. 35

7. In an organ-action, a solenoid having a central opening therethrough, a tubular core movably disposed in the said opening, a valve operative by the said core and adapted to close the opening of the solenoid at one end of the latter, and means for directing a blast of air through the core and opening of the solenoid. 45

8. In an organ-action, a solenoid having a tube inclosed thereby and forming a conduit means therethrough, a tubular core movably disposed in the solenoid-tube, a duplex valve operative by said core and adapted to be seated by the movement of the latter against one extremity of the solenoid-tube, means for directing a blast of air through the tube and core, and a separate part against which the valve is automatically seated when the solenoid is de-energized. 50 55

In testimony whereof I have hereunto set my hand in presence of two subscribing witnesses.
